KEY SEAT CUTTER

Charles O. Van Note, Jr., Palos Verdes Estates, Calif., assignor to Servco Engineering, Ltd., Long Beach, Calif., a corporation of California

Application December 7, 1953, Serial No. 396,654

2 Claims. (Cl. 255—27)

This invention relates to a tool for cutting and thereby enlarging a key seat in a well bore and which seat frequently acts to prevent upward retraction of the drilling tool on the end of a long string.

In the rotary drilling of wells, particularly deep wells, the drill string, because of its great length, flexes to wear a groove or key seat in the side wall of the bore. The string being of smaller diameter than the drill collar at the end thereof, forms a seat that is smaller in diameter than the diameter of the drill collar. Consequently, it is difficult and frequently impossible to withdraw the drill from the bore because the same becomes wedged in the key seat thus formed as the string is withdrawn upwardly.

Only by enlarging the key seat to a size that will permit upward passage of the drill collar can the latter be withdrawn with easy facility. Jar types of reaming tools have been devised for this purpose and it is an object of this invention to provide an improved form of such tool which enables successive reaming enlargement of a key seat in a facile and expeditious manner.

Prior jar tools usually embody a reaming sleeve that is either keyed to a mandrel on which mounted to, at all times, turn with the mandrel, or is rotationally free of the mandrel and incapable of being rotated. Another object of the invention is to provide a key seat cutting tool that is provided with a reaming sleeve that may be keyed to or freed from the mandrel, as desired, thereby enabling determination as to whether or not the sleeve is stuck or wedged in a key seat.

Another object of the invention is to provide key seat cutter means that employs both the weight of a drill string and the stored energy therein that results from placing said string in torsion to obtain a sudden release between the string and a member that is wedged in a key seat and, thereby, create a sharp and powerful member-dislodging force that frees the latter from the seat in which wedged.

If any point of a drill string becomes wedged or seized in a well bore, that portion of the string above the point of such seizure and extending to the surface of the bore is capable of being torsionally wound from the surface, thereby imparting a strong torsional force on said portion of the string. If this torsion is being held or retained by a releasable connection between a member that is seized in the bore and the string itself, and release of the connection may be effected by an increase of the force of weight of the wound-up string portion upon said connection, then, by holding the torsion from above and at the same time lowering the string, the weight of the latter, when suddenly released, allows the string to drop with a strong jarring force that acts on the seized member in a direction to downwardly dislodge the same. Accordingly, a still further object of the invention is to provide novel and improved releasing means as above indicated, that is effective, under the forces applied by the weight and torsion on a drill string, to suddenly release the

2

weight of the string to act on a reaming collar that is wedged in a key seat and jar the same loose.

A further object of the invention is to provide a key seat cutter that includes a reaming sleeve that can be "worked" upwardly through a key seat in successive stages by effecting successive enlargements of the key seat.

The invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawing merely shows and the following description merely describes, one embodiment of the present invention, which is given by way of illustration or example only.

20 In the drawing, like reference characters designate similar parts in the several views.

Fig. 1 is a partial elevational and partial sectional view of a key seat cutter according to the present invention.

25 Fig. 2 is a similar view showing the cutter in another position.

Figs. 3 and 4 are enlarged cross-sectional views as taken on lines 3—3 and 4—4, respectively, of Fig. 1.

30 Fig. 5 is a similarly enlarged longitudinal sectional view of the lower end of a reaming sleeve shown in the other figures.

35 The key seat cutter that is illustrated comprises, generally, a mandrel 10 provided adjacent its lower end with key means 11, and a reaming collar or sleeve 12 on said mandrel 10 and provided with means 13 cooperating with the key means 11 to key the sleeve to the mandrel or release the same, as desired.

40 The mandrel 10 is formed as an element of a drill string 14 which, in the usual manner, carries a drill collar 15 at its lower end. While shown with a pin 16 directly engaged in the box 17 of said drill collar, a portion of the drill string may be interposed so that mandrel 10 is spaced above the drill collar, as desired. A similar pin and box is provided between the upper end of the mandrel and the lower end of the drill string 14.

45 The mandrel 10 that is illustrated comprises an elongated round-sectioned stem 18, an enlarged portion 19 at the upper end of said stem defining a downwardly-facing annular shoulder 20, and an enlarged portion 21 at the lower end of the stem defining an upwardly-facing annular shoulder 22. In practice, portion 19 is made of a diametral size approximating the largest diameter of the drill string 14 and portion 21 of a diametral size approximating that of drill collar 15. Since the drill collar is usually substantially larger than the drill string, shoulder 22 is larger in diameter than shoulder 20. Also, the mandrel is axially hollow as indicated at 23, to provide the usual passage for fluid circulated through the drill string.

50 60 The key means 11 is shown as diametrically opposite keys 24 that are preferably integrally formed on stem 18 adjacent but in spaced relation to shoulder 22. Each key 24 is preferably straight-sided, as shown, and at its lower portion is provided with a sloping face 25 of material degree. The slope shown approximates 40° with respect to the horizontal, although the angle of slope may vary. The upper end of each key is provided with a sloping face 26 that is of less degree than the slope of face 25, being in the nature of 15°. In the interest of

65 70 strength, said keys 24 are formed as the stem 18 is machined to its smaller size from the initial larger size

of portion 21. In some cases, sufficient strength may be achieved by welding said keys 24 onto stem 18.

The reaming sleeve or collar 12 comprises a tubular member that is substantially shorter than mandrel stem 18 and, in order to assemble the same onto the stem, is initially formed as two similar longitudinal halves that are connected by welds 27, as best seen in Fig. 3.

The upper end 28 of reaming collar 12 is formed to be of approximately the diametral size of mandrel part 19 and the lower end 29 of the diametral size of the larger mandrel part 21. As shown, said collar may be provided with an intermediate part 30 that has a diametral size between that of collar ends 28 and 29 and it will be obvious that said intermediate part 30 may be omitted or two or more differently sized intermediate parts may be provided. In any case, the reaming collar 12 is formed as a stepped tubular member that is enlarged in successive stages from the top down, the increments of enlargement depending on the number of stepped parts and the difference in diametral size of mandrel parts 19 and 21. Each stepped part of the collar 12 is preferably provided with reaming projections 31 which may vary in their form and are designed to enlarge a key seat when rotated therein. In this case, the reaming projections on the smaller collar end 28 are made of such size as to enlarge a key seat to the approximate size of intermediate collar part 30, and the projections of the latter part of a size to enlarge a key seat to the approximate size of the larger collar end 29. Of course, the above-indicated sizes of collar projections may be varied, providing the same enlarge a key seat, in successive stages, until said seat is large enough to pass the drill collar.

The means 13 is provided in the reaming collar 12 adjacent its lower end and is shown as comprising oppositely disposed openings 32 substantially larger than keys 24 and in which said keys are adapted to be disposed. Each opening 32 is formed to have a straight side 33 and a bottom edge or side that is formed with a sloping edge 34 at an angle substantially the same as that of key face 25. The shape of the other sides or faces of said openings 32 is immaterial, provided the keys 24 are freely and loosely received in said openings.

It will be noted from Fig. 3 that the keys project less than the thickness of the collar. A commensurately shallow slot 35 extends from the bottom of each opening 32 to the lower end of the collar, as best seen in Fig. 5, and is of a width and depth to freely pass said keys. As shown, each said slot 35 is circumferentially spaced from walls 33, the sloping faces 34 extending between the lower ends of said walls and said slots. It will be obvious that the depth of said keys 24 may approximate the thickness of the reaming collar, in which case slots 35 will be cut completely through said collar.

Operation

During normal rotary drilling, the reaming collar is positioned, as shown in Fig. 1, resting on shoulder 22 and with keys 24 in collar openings 32. Said collar merely rotates with the drill string in a clockwise direction, as seen from above, so that the threaded joints in the drill string may be maintained.

Should the well bore have a key seat therein, when withdrawing the drill string the upper collar part 28 is wedged first in said seat and prevents continuation of the withdrawal. In such case, a clockwise torque is placed on the drill string in some usual manner, as by tongs, from above. This brings the keys 24 into firm engagement with the sides 33 of openings 32 in the collar.

Since the drill collar 12 is firmly wedged in the key seat, the torque applied to the drill string results in said string winding up torsionally in the manner of a torsional spring. While this torque is maintained, the string is lowered. As a result of such lowering, the sloping faces 25 of keys 24 come to rest on the sloping faces 34 of

openings 32. It will be realized that the drill string, initially elongated because in free suspension, becomes foreshortened as the downward movement of the keys is arrested and more and more of the string weight comes to bear on the points of engagement between faces 25 and 34.

The weight of a drill string will vary with its length but, in any case, will be many thousands of pounds. This weight on the sloping faces 34 of the collar 12 gradually overcomes the torsional force on the drill string and the keys 24 of the latter cam downwardly along sloping faces 34 until said keys lose contact with said sloping faces. Thus, the force of the weight of the string becomes effective to overcome the torsional force of the string, the keys 24 moving counter to the direction of the torsion by reason of said cam-wedging engagement of faces 25 and 34. Then, as keys 24 become aligned with slots 35 in collar 12, the full weight of the drill string is released with trigger-like suddenness and the string drops off the sloping faces 35 and causes shoulder 20 of the drill string to strike the top edge of collar 12 with a sudden force represented by the full weight of the drill string. This force is normally great enough to dislodge said collar from a key seat. In any case, the above can be repeated, if necessary, until dislodgement results. The repeat operation starts with an upward withdrawal of the string until keys 24 encounter the lower edge of the collar 12. Then, by rotating the string while continuing upward withdrawal thereof, the keys 20 find and enter slots 35; upward withdrawal of the string is arrested when the keys encounter the upper edges 32a of openings 32. Now, torsion is applied to the string, as before, and the string lowered, to repeat the jarring operation.

While jarring devices have, heretofore, employed a drop of the drill string, the jarring forces were conventionally applied by alternate raising and releasing of the string from above. There was no sudden release of the full force of the weight as in the present instance, but rather a gradual use of the weight because of the elongation and contraction inherent in a long drill string.

When dislodged, as above, the reaming collar 12 may first fall onto keys 24. However, only a partial rotation of the string is needed to allow the keys to slip upwardly into openings 32. Now shoulder 22 encounters the lower edge of the reaming collar 12, as before. Since torsional force on the collar part 28 had effected its dislodgement from the key seat, the collar will pass upwardly as the drill string is being again withdrawn to bring the intermediate part 30 of the collar into engagement with said seat. Now, if this part becomes wedged, the key seat is further enlarged by repeating the above-described operation. Of course, if the keys 24 do not find grooves 35, when the string is being withdrawn, said keys will serve the same purpose as shoulder 22 and carry the collar 12 upward. In this case, before again starting the jarring operation, the keys are withdrawn, as before described, into engagement with the upper edges 32a of openings 32. To minimize friction between the sloping face 26 of each key and the lower edge 36 of the collar when the string is being upwardly moved, a sloping face 37 is provided where said lower collar edge 36 is adjacent to each slot 35. Thus, the keys are easily led or guided into slots 35 because the corner 38 of each key is guided into engagement with the longitudinal edge 39 of each slot and inadvertent slipping of the keys past the slots is obviated.

From the foregoing, it will be realized that the key seat is finally enlarged by the lower end of the reaming collar to a size that will permit free upward passage of the drill collar 15. Said successive operations need only be performed if wedging occurs since there may be instances when the next larger portion of the collar may,

during raising of the drill string, pass through the key seat as previously enlarged.

It will be evident from the foregoing that a key seat in a well bore is enlarged in successive stages to a size that will freely pass drill collar 15 and the bit carried thereby.

While sloping face 34 is shown as of relatively small extent, it will be clear that the same actually constitutes a portion of a helix along which key face 25 may move under force of the weight of the drill string. Therefore, it is intended that face 34 represent a helical cam which may be short, as shown, or substantially longer in extent. Broadly, therefore, face 34 may be considered as weight-arresting means that yields to effect sudden release between mandrel 18 and reaming sleeve or collar 12 while torsion is applied to a string in which said collar is embodied and the weight of the string is released from above and is supported by the arresting means.

Because of the ability to free the drill string from the reaming collar, it is a simple matter to determine whether inability to withdraw the string results from wedging of the collar in a key seat. By slackening off on the string to lower the keys 24 below the reaming collar, such a check can be made since, if the string can be freely rotated from above, the reaming collar is wedged in a key seat. If the string cannot be rotated freely, then there is another cause that resists string withdrawal.

Prior well reams or key seat enlargers operate on the principle of dislodging successively more elevated portions of a key seat and always on a constant diameter of enlargement. This disclosure includes a method of key seat enlargement that is based, not on constant-diameter enlargement, but rather on enlargement to successively larger diameters in easy, tool-sparing stages.

While I have illustrated and described what I now contemplate to be the best mode of carrying out my invention, the construction is, of course, subject to modification without departing from the spirit and scope of the invention. It is, therefore, not desired to restrict the

invention to the particular form of construction illustrated and described, but to cover all modifications that may fall within the scope of the appended claims.

Having thus described my invention, what I claim and desire to be secured by Letters Patent is:

1. A key seat enlarging tool comprising an elongated mandrel having upper and lower shoulders, a reaming collar rotatably and slidably mounted on said mandrel, a key on said mandrel adjacent but spaced upwardly from said lower shoulder, said reaming collar being normally in engagement with said lower shoulder and having a recess wider than said key, receiving said key, and provided with a side face opposed to a side of said key to establish a rotary driving connection between said mandrel and collar, said collar having a keyway therein extending from the lower end thereof into said recess and being circumferentially offset from said side face of said recess, the length of said collar being less than the distance between said key and the upper shoulder.
2. A key seat enlarging tool as defined in claim 1 wherein a first cam surface slopes downwardly from the lower end of said side face to the upper end of the adjacent side of said keyway, said key having a corresponding cam surface at its lower edge arranged to slidably engage said first cam surface.
